UNITED STATES PATENT OFFICE

168,234

FLUSH DOOR

Alphonse Mastrangelo, Fitchburg, Mass., assignor
to Angel Novelty Company, Fitchburg, Mass.,
a corporation of Massachusetts

Application January 22, 1952, Serial No. 18,168

Term of patent 3½ years

(Cl. D13—1)

To all whom it may concern:

Be it known that I, Alphonse Mastrangelo, a citizen of the United States, residing at Fitchburg, Massachusetts, have invented a new, original, and ornamental Design for Flush Door, of which the following is a specification, reference being had to the accompanying drawing, forming part thereof.

Fig. 1 is a view in front elevation of a flush door showing my new design, and Fig. 2 is an enlarged section on line 2—2 of Fig. 1. The opposite side of the flush door is the same.

I claim:

The ornamental design for a flush door, as shown and described.

ALPHONSE MASTRANGELO.
